UNITED STATES PATENT OFFICE.

DANIEL SCHMID, OF MILWAUKEE, WISCONSIN, ASSIGNOR TO PROGRESSIVE MANUFACTURING CO., OF MILWAUKEE, WISCONSIN, A CORPORATION OF WISCONSIN.

BOTTLE-WASHING MACHINE.

1,095,290.

Specification of Letters Patent.

Patented May 5, 1914.

Application filed January 14, 1911. Serial No. 602,561.

To all whom it may concern:

Be it known that I, DANIEL SCHMID, a citizen of the United States, residing in Milwaukee, in the county of Milwaukee and 5 State of Wisconsin, have invented new and useful Improvements in Bottle-Washing Machines, of which the following is a description, reference being had to the accompanying drawings, which are a part of this 10 specification.

This invention has for its object to provide a bottle washing machine which will produce successive cleaning operations upon a series of traveling bottles without interfering with the continuous feed motion of 15 said bottles through the machine.

Another object of the invention is to accomplish the foregoing by means of a table which is provided with a number of yielding 20 bottle engaging members to engage the mouths of the bottles and is adapted to reciprocate vertically so as to close upon and to retreat from said bottles and which is also adapted to reciprocate horizontally so 25 that the said members may travel with the bottles while in engagement therewith and move to a new position to engage a new set of bottles when the members are in their released position.

30 Another object of this invention is to provide such table with a number of the members having bottle washing means therein to project into the bottles and turn in the same while spraying a cleaning liquid or a rinsing liquid, such members operating successively on the series of bottles.

Another object of the invention is to provide a washing machine with rotary brushes for thoroughly cleaning the exterior of the 40 bottles during their travel into the machine and through the machine.

Another object of the invention is to improve upon the details of construction of bottle washing machines.

45 With the above and other objects in view the invention consists in the bottle washing machine herein claimed, its parts and combinations of parts and all equivalents.

Referring to the accompanying drawings 50 in which like characters of reference indicate the same parts in the different views: Figure 1 is an elevation of a bottle washing machine constructed in accordance with this invention, as seen from one side, the table being shown in its lower position in transit

from one set of bottles to another. Fig. 2 is a similar view thereof as seen from the other side of the machine, the cleaning table being in its upper or working position; Fig. 3 is a plan view, parts being broken away 60 for clearness of illustration. Fig. 4 is a vertical transverse sectional view on no regular plane; Fig. 5 is a view similar to Fig. 2 of parts somewhat similar to Fig. 1, but showing parts in their positions when 65 the cleaning table engages the bottles and just before the cleaning tools are inserted in the bottles. Fig. 6 is an end elevation of the inclined cleaner for the exterior of the bottles which operates on them just before 70 they enter the conveyer of the machine; Fig. 7 is a detail plan view of the cleaning table traveling frame; Fig. 8 is an enlarged detail view of the spindle supporting and driving mechanism; Fig. 9 is a further detail view of the spindle driving mechanism 75 in vertical section; Fig. 10 is a view of the same parts in plan; Fig. 11 is a detail view of the adjusting mechanism for varying the extent of upward movement of the spindles 80 to accommodate bottles of different sizes; and, Fig. 12 is a further detail view of such adjusting mechanism.

In these drawings 20 indicates a frame which comprises two side members substantially alike, forming supports for the various parts of the mechanism and bearings for the several shafts which extend from one side of the machine to the other.

One of the most important features of 90 this invention consists of a conveyer which preferably is constantly driven and which receives bottles in the openings of bottle carrier plates thereof, such bottles receiving preliminary outside cleaning as they 95 pass down an inclined chute into the openings of the bottle carriers and continuing with the conveyer in uninterrupted travel over a series of cleaner tools which automatically clamp therewith and enter the interior of the bottle while injecting cleaning or rinsing liquid therein, such cleaning device traveling with the bottles for a distance and then returning to take up a new 100 position whereby each bottle is subjected to the cleaning and rinsing devices successively and then passes out of the machine where it may be inspected and removed by an operator. Such conveyer comprises a pair of chains 21 which ascend at an incline from 105 110

sprocket wheels 22 at the lower part of one end of the machine and are held against sagging by guide strips 23, and then pass over sprocket wheels 24 and run in a horizontal direction still supported by guide strips 23 until they pass around sprocket wheels 25 mounted on brackets 26 beyond the other end of the machine and then descend and return to the sprocket wheel 22 after passing around a sprocket wheel 27 which is provided with adjusting screws 28 for tightening the conveyer. The conveyer chains are driven by means of a sprocket wheel 29 on the same shaft with sprocket wheels 24, which is connected by a chain 30 with a sprocket wheel 31 on a shaft 32. The shaft 32 in turn is driven by a gear wheel 33 which is mounted thereon and meshes with pinion 34 carrying a larger gear wheel 35 in mesh with a pinion 36 on a drive shaft 37 which is driven in any suitable manner, as by a belt pulley 38 connected with some engine or motor. The bottle carriers 39 are preferably in the form of wooden plates having tapering openings therethrough to receive the bottle necks, as clearly shown in Figs. 4 and 5, and are pivotally connected with the chains 21 so as to be capable of passing over the sprocket wheels in the manner shown in Figs. 1 and 2.

The bottles are delivered to the openings in the bottle carrier at regular intervals, when such openings are in position to receive them, by a preliminary cleaning mechanism. A shaft 40 journaled across bracket frames 41, has a sprocket wheel 42 on one end, as best shown in Fig. 6, which is connected by a chain 43, Fig. 2, with sprocket wheel 44 on the drive shaft 37 and this shaft 40 is provided with a number of spiral wheels 45 meshing with corresponding spiral wheels 46 on the lower ends of a series of inclined roller shafts 46 which are mounted in the bracket frames 41 and carry rolls 48. The bottles are placed upon these rollers, or rather in the spaces between them, so that each bottle bears on two of the rollers and the motion of the rollers is imparted to the bottles, said bottles being held temporarily against sliding off of the inclined rollers by a shutter 49 which stands in their path, as shown in Figs. 1 and 6. At the proper time the shutter is withdrawn to permit the bottles to slide down the incline of the rollers and along an inclined guide 50 into the openings of the bottle carriers which are then in position to receive them. This automatic tripping operation of the shutter is produced by reason of said shutter being mounted on the ends of levers 51 which are fulcrumed in the bracket frames 41, one of said levers having a spring pressed rod 52 extending from it and passing through a guide 53 and the frame 20 with its bent end

in a position to be engaged by a trip lug 54 on the gear wheel 33, the engagement of said trip lug with the end of rod 52 serving to lift the rod and swing the levers 51 to withdraw the shutter, as shown in Fig. 2, and permit the bottles to slide downwardly into the bottle carriers.

The turning movement of the bottles produced by the rotation of the rollers 48 on which they rest while detained by the shutter is for the purpose of bringing their entire outer surface into the action of rotary cleaning brushes 55 which are mounted in the bracket frame 41 and are driven from the roller shafts 47 by a chain passing around sprocket wheels 56 and 57 on the ends of said rotary brushes and said roller shafts respectively, as shown in Figs. 1, 2 and 3. At the same time that the brushes rub against the turning bottles, streams of water or other cleaning fluid, play upon the bottles from pipes 58, as seen in Fig. 1. When the bottles have been discharged from the preliminary cleaner by the withdrawal of the shutter 49, the rod 52 leaves the trip lug 54 and the shutter is returned to its position shown in Fig. 1 for retaining the next set of bottles placed on the rollers by the operator.

After the bottles enter the bottle carrier, they travel upwardly to the horizontal portion of the travel of the conveyer where they pass over a table which carries the cleaning devices and which is given an up and down movement as well as a horizontal movement. At the same time the bottles pass beneath a bottle clamping frame which has corresponding movements imparted to it to clamp the bottles from above at the same time that they are clamped from below by means of the table and its parts. A horizontal beam 59, as seen in Fig. 1, and a corresponding horizontal beam 60, as seen in Fig. 2, are suspended by means of links 61 at their opposite ends, which links, as shown in Fig. 7, are mounted on the ends of cross rods 62 which connect the ends of said horizontal beams 59 and 60 to form a rectangular frame. The links 61 are pivotally mounted on the frame 20 at their upper ends and being of the same length, the rectangular frame is capable of swinging though remaining horizontal at all times. One of the links 61 has an upwardly extending projection 63 converting it into a lever for causing the swinging motion of the rectangular frame by having a roller 64 on its end traveling in a cam channel 65 on the face of gear wheel 33, previously referred to. At the other end of the rectangular frame, it is steadied in its movements by means of short arms 66, Fig. 5, having slotted connections with the cross rods 62 and being carried by rod 67 which is mounted in the frame 20. The horizontal beam 59 has an opening or

sleeve portion 68 through which a vertical guide rod 69 passes and the horizontal beam 60 is provided with a slotted upward extension 70 and a slotted downward extension 71, both preferably parts of an integral casting therewith, and in all forming a guide frame of the shape of a cross. The vertical guide rod 69 is clamped to the horizontal beam 59 by means of a set screw 68', as shown in Fig. 7, and at its lower end it is connected with the downward extension 71 of the other horizontal beam 60 by means of tie rods 71'. A table 72 is slidably mounted on the vertical guide rod 69 and carries a pair of guide rollers 73, one above the other, which fit within the groove of the guide beam 60 so that said table is free to move vertically. Likewise a bottle clamping frame 74 is slidably mounted by loosely fitting on the vertical guide rod 69 and has a pair of rollers 75 fitting within the slot of the guide beam 60. The vertical movements of the table 72 and the bottle clamping frame 74 are accomplished automatically from the gear wheel 33 by means of a lever 76, Fig. 5, which is loosely mounted on a shaft 77 extending across the rectangular frame and journaled in the beams 59 and 60, said lever having a roller 78 on its end to normally ride upon a concentric flange 79 on the wheel 33 but which is adapted to ride off of said flange at a certain point in the cycle of operation and then move toward the center of the wheel 33, a short distance, as shown in Fig. 1, where it remains until again engaged by the inwardly turned end of flange 79 by which it is returned to the position in which it is shown in Fig. 5. This lever 76 has a turn buckle connection 80 with a lever 81 which is fixed on the shaft 77 with its shorter end connected by a link 82 with the table 72, the other end of shaft 77 being similarly provided with a crank arm 83 which is likewise provided with a link connection 84 with the table 72 whereby the swinging movements of the lever 76, produced by its roller engagement with the flange 79, are imparted to the lever 81 through the turn buckle connection 80 and result in a vertical sliding movement of the table 72 by reason of said link connections.

The adjustment of the turn buckle 80 serves to vary the normal elevation of the table 72 and adapt the machine for bottles of different lengths. The shorter end of lever 76 is connected by a link 85 with a sector-shaped end of a hand lever 86 which is fixed on a shaft 87 journaled in the beams 59 and 60, said connection being adjustably obtained by means of a clamp member 88 capable of riding in an arc-shaped slot 89 of the hand lever 86. The hand lever 86 has a link 90 connecting it with the bottle clamping frame 74 and the other end of shaft 87 has a crank arm 91 on it with a link

connection 92 with the bottle clamping frame 74, as shown in Fig. 2. The movements of the lever 76 are thus also transferred to the bottle clamping frame 74 by means of the shaft 87 and its link and lever 70 connections 85 and 86 with said lever 76. By adjusting the clamping member 88, forming a connection between the link 85 and the hand lever 86, to a different position in the arc-shaped slot 89, the normal position of the bottle clamping frame 74 may be varied to accommodate bottles of different sizes, the handle on hand lever 86 being provided to facilitate such adjustment.

As best shown in Fig. 4, the table 72 comprises an upper plate spaced from a lower plate and provided with openings of sufficient size to receive the bottle necks and between these plates are telescoping spring-pressed funnel-shaped compressible members 93 which are engaged by the mouths of the bottles as the table rises in its vertical movements above described and yield so as to tightly fit therewith. The bottle clamping frame 74 is provided on its under surface with flaring four-pronged bottle seats 94, as seen in Fig. 3, to engage the upper ends of the bottles and center them and hold them steady in their engagement with the members 93, as shown in Fig. 5, when said bottle clamping frame 74 is lowered by the means just described. The bottle clamping frame, as shown in Fig. 3, is formed of two portions spaced apart, the intervening space being occupied by a rotary brush 95 which is journaled in the bottle clamping frame and is driven by having a sprocket wheel 96 on its end engaging a chain 97, Fig. 2, which passes around a sprocket wheel 98 on shaft 37 and also around a chain tightener 105 sprocket wheel 99 which is suspended from the frame 70 by means of a link 100. The purpose of this rotary brush 95 is to clean the upper ends of the bottles as they pass therebeneath. This brush may be assisted in its cleaning operation by the presence of a spray of water or other cleaning liquid, as with the brushes 55.

When the bottles are clamped between the table and the bottle clamping frame, cleaning instruments are thrust into them and turned to scour the interior of the bottles and at the same time, cleaning and rinsing liquids are injected into the bottles, preferably by means of said cleaning tools.

The shaft 32 has a crank arm 101 at each end thereof which crank arms are connected by links 102 with levers 103 at an intermediate portion thereof, this connection being shown in detail in Figs. 11 and 12 as constituting a shaft 104 passing through elongated slots 105 in the levers 103 and connecting the two levers 102 at the opposite sides of the machine, said shaft having a sleeve 106 keyed thereon and terminating in pinions 130

107 which mesh with racks 108 on the levers 103, whereby the turning of the shaft 104, which is accomplished by means of a hand wheel 109 on its end, serves to cause it to travel along the slots 105 to bring the pivotal connection of the links 102 with the levers 103 nearer to or farther from the fulcrums of said levers, for such links 102 are pivotally mounted on the shaft 104 with loose sleeves therebetween and washers on either side thereof. When the desired adjustment is accomplished, the parts may be locked by turning a hand nut 110 which is threaded on the shaft 104 and tends to clamp the parts together. The ends of the levers 103 are provided with elongated slots 111, which engage rollers carried by studs 112 on a gear casing 113, as shown in detail in Figs. 9 and 10. This gear casing is loosely mounted on the vertical guide post 69 and has a sleeve 114 passing through the slot of guide frame extension 71, said gear casing being guided in said slot by having a pair of rollers 115 bearing against the walls thereof. One of the rollers 115 is mounted on the sleeve 114 and said sleeve passes through the slot 111 of the other lever 103. It will be seen that the gear casing 113 is vertically movable on the guide rod 69 and in the guide frame 71 in the same manner as the table 72 and the bottle clamping frame 74 and that the turning of the cranks 101 causes the levers 103 to swing by their link connections 102 therewith and thus slide the gear casing 113 vertically to a greater or less extent, according to the adjustment of the pivotal connection of said links with said levers by means of the hand wheel 109.

The gear casing 113, as shown in Fig. 9, forms a closed oil chamber in which are mounted a pair of gear wheels 116 carried by studs 117, said gear wheels meshing with each other and one of them carrying a beveled gear wheel 118 meshing with beveled gear wheel 119 on a shaft 120 which passes through the sleeve 114 and is driven by a sprocket wheel 121. The sprocket wheel 121, as shown in Fig. 2, engages throughout the travel of the gear casing 113 with a chain 122 which is driven by a sprocket wheel 123 on shaft 37 and passes around an idler sprocket wheel 124 mounted on the frame extension 71, there being a chain tightener roller 125 suspended from the frame by means of a weighted lever 126 for keeping the chain 122 taut at all times. Again referring to Figs. 9 and 10, the gear wheels 116 mesh with pinions 127 on vertical tubular spindles 128 which have their lower ends fitting in step bearings 129 within the gear casing, as shown in detail in Fig. 8, and have their upper ends passing through packing glands provided for them in the bottom of the table 72, where, as shown in Fig. 4, they are provided with brushes 130

normally contained within the telescoping, yielding tubular members 93, but which are projected within the bottles when the gear casing 113 is lifted, as just described. These spindles with their brushes are turned through their gearing connections so that the brushes, when projected into the bottles, thoroughly scrub the interior thereof. As shown in Fig. 8, the lower ends of the spindles 128 are lubricated by means of wicks 131 which lead from the interior of an oil well 132 supplied with lubricant through a bent tube 133, the drain from such step bearing being taken off through an opening 134 into the top portion of the gear casing from which it runs into a well where the beveled gear 19 dips into it and by splashing the oil throughout the gear casing serves to thoroughly lubricate all of the gearing. The bottom of the gear casing is provided with water passage ways 135 through which tubular plugs 136 pass to constitute a communication between said water passage ways and the bores of the spindles 128, said tubular plugs passing through packing glands 137 in the lower ends of the spindles 128 so as to prevent a leakage of water into the gear casing. The gear casing 113 carries bracket extensions 138 at its ends which support water supply pipes 139 having vertical tubes 140 projecting upwardly therefrom and entering the table 72 in the same manner as the spindles 128 for injecting water or other cleaning fluid into the bottles before and after the treatment with the brushes. These water pipes 139, as well as the water passage ways 135 may be supplied with water or other cleaning liquid by means of flexible hose pipes 141 which may be automatically controlled as by a valve 142, shown in Fig. 1, having a roller engagement with a cam arm 143 projecting downwardly from the beam 59 so that when the gear casing 113 is in its lowermost position, the valves are closed, but as soon as the gear casing is raised so that the brushes and water tubes are projected in to the bottles, said valves will be opened automatically to inject their spray of liquid into the bottles.

After the bottles pass away from the cleaning mechanism, they travel beyond the frame of the machine to a position in which they may be readily inspected and from which they may be conveniently removed by an operator at the discharge end of the machine. To prevent the bottles being carried by the conveyer around the sprocket wheels 25 in event of the operator at the discharge end of the machine neglecting to remove them in time, an automatic stop is provided to disconnect the driving connections of the machine and bring the mechanism to a stop at such times. The shaft on which the sprocket wheels 25 are mounted is tubular and a rod 144 passes through it with 139

crank arms 145 on its end which carry a rod 146 extending across the path of the bottles on the conveyer so as to be engaged thereby and swung. This causes a crank arm 147, 5 forming an extension of one of the arms 145, to push upwardly on a link 148 and thereby swing a bell crank lever 149 to which it is attached, Fig. 3, so as to throw out of connection a clutch member 150 which connects 10 the pinion 36 with the drive shaft 37, and thus stop the motion of all of the machine except the turning of the brushes which continues because of their direct driving connection with the drive shaft. The conveyer 15 being arrested in its movement does not carry the bottles around the sprocket wheels 25 so that there is no danger of the bottles falling out of the bottle carriers.

The operation of the several parts of the 20 machine has been fully described incidental to the description of their construction, but briefly reviewed, is as follows: The bottles are placed by the operator upon the rotating rollers 48 where they receive an external 25 cleaning by the rotary brushes 55 which brush against them while they are being turned by the rollers 48 and while they are subjected to the spray of cleaning liquid from pipe 58. When the conveyer reaches a 30 position in which it is adapted to receive the bottles from the preliminary cleaner, the shutter 49 is withdrawn automatically and the bottles slide down into the openings provided for them in the bottle holders and are 35 carried along with the conveyer until they come between the bottle clamping frame and the table, when these mechanisms are moved toward each other by the operation of lever 76 so that the bottles first become clamped 40 between them and receive a preliminary internal washing from the first set of cleaning liquid supply tubes 140, a strong alkaline solution being preferably injected at this 45 point in the cycle of operation. While the 50 bottles are being clamped by the bottle clamping frame and the table, these mechanisms move along with them, the entire mechanism suspended by the links 61 swinging 55 in unison with the motion of the bottles 60 because of the action of lever 63. When the lever 63 arrives at the steep pitch of its cam channel in the gear wheel, 33, as shown in Fig. 1, it returns the swinging parts to their original position, but just previous thereto, 65 the bottle clamping frame and the table have been moved away from the bottles by the lever 76 riding off of the flange 79, the weight of the table and its parts being sufficiently greater than the weight of the bottle 70 clamping frame, which it counterbalances, to accomplish this purpose at such time. When the swinging parts are returned to their advance position, the bottles are again clamped between the bottle clamping frame and the 75 table, but this time the bottles which were

before clamped by the first set of members 93, are now clamped by the second set and the brushes 130 are projected into them and rapidly turned while the cleaning fluid is being sprayed from openings in the tubular 70 spindle within or near the brush portion and this operation is repeated with the successive clamping members, the final engagement of the bottles being preferably for the injection of clear water for rinsing the bottles. The 75 bottles are then carried to the discharge end of the machine where they are removed and should the operator neglect to remove them in time, they will automatically stop the movement of the conveyer and prevent 80 breakage.

With this machine the great advantage is gained by having the travel of the bottles continuous instead of intermittent, for no time is lost and the operation is uninterrupted from the time the bottles are placed in the machine until they are removed therefrom. The bottles become thoroughly 85 cleaned outside and have labels removed 90 therefrom by the action of the rollers 48 and the brushes 55 before they enter the conveyer and then are successively treated chemically and mechanically to thoroughly cleanse the interior, the only portions of the exterior of the bottle which are not thoroughly cleaned 95 before the bottle enters the conveyer, the upper ends, being cleaned by the brush 95 in their passage between the bottle clamping frame and the table.

All of the parts are made adjustable to accommodate bottles of various sizes so that the machine may be quickly changed from one class of work to another.

What I claim as new and desire to secure by Letters Patent is:

1. A bottle washer, comprising a frame, a continuously moving bottle conveyer passing through the frame, a suitably driven wheel mounted on the frame and containing a cam, links suspended from the frame, beams connected with the said links and the said lever to receive a swinging motion from the cam in a direction to cause it to alternately move with and counter to the bottle conveyer, a guide rod carried by the swinging beams, a table slidably mounted on the guide rod, cleaning mechanism carried by the table, and means for sliding the table on the guide rod toward the bottles while the beams are swinging with the movement of the bottle conveyer.

2. A bottle washing machine, comprising a frame, a continuously moving bottle conveyer traveling through the frame, a suitably driven wheel mounted on the frame having a cam, a lever fulcrumed on the frame with a roller traveling on the cam, links suspended from the frame, beams connected with the said links and with the said lever whereby they are suspended and given a 125 130

- swinging movement to cause them to alternately move with and counter to the bottle conveyer, a guide rod carried by one of the beams to move therewith, a table slidably mounted on the guide rod, bottle cleaning mechanism carried by the table, a lever fulcrumed on one of the beams and having connection with the table, a roller, and a flange on the wheel for engaging the roller to swing the lever and cause the table to slide on the vertical rod toward the bottle conveyer.
3. A bottle washing machine, comprising a frame, a continuously moving bottle conveyer passing through the frame, a suitably driven wheel on the frame having a cam and an interrupted annular flange, a lever fulcrumed on the frame with a roller traveling on the cam, links suspended from the frame, beams carried by the links and said lever, a guide rod on one of the beams, a table slidably mounted on the guide rod, bottle cleaning means carried by the table, a lever fulcrumed on one of the beams and having a roller to engage the said flange, a connection between said lever and the table, a bottle clamping frame slidably mounted on the guide rod, and a connection between the table and said lever and between the bottle clamping frame and said lever for causing said table and bottle clamping frame to move toward each other and clamp the bottle between them.
4. A bottle washing machine, comprising a frame, a continuously moving bottle conveyer passing therethrough, a suitably driven wheel mounted on the frame and provided with a cam groove and a broken annular flange, a lever fulcrumed on the frame and provided with a roller engaging the cam groove, links on the frame beams suspended by the links and the lever, a guide rod carried by one of the beams, a table slidably mounted on the guide rod, bottle cleaning means carried by the table, a bottle clamping frame also slidably mounted on the guide rod, a lever fulcrumed on one of the beams and having a roller for engaging the annular flange, an adjusting means on said lever, a link connected to said lever, a clamping member thereon, a hand lever fulcrumed on one of the beams and provided with an arc-shaped slot for engagement with the clamping means, a link connecting the hand lever with the bottle clamping frame, a lever fulcrumed on one of the beams and connected with the adjusting means, and a link connecting said last mentioned lever with the table.
5. A bottle washing machine, comprising a frame, a continuously moving bottle conveyer passing through the frame, a shaft journaled in the frame, a wheel on the shaft provided with a cam groove and a broken annular flange, a lever fulcrumed on the frame provided with a roller engaging the

cam groove, links suspended from the frame, beams carried by the links and the lever, a guide rod on one of the beams, a table slidably mounted on the guide rod, a bottle frame also slidably mounted on the rod, a lever fulcrumed on one of the beams and having a roller engaging the annular flange, connections from said lever to the table and the bottle clamping frame, cranks on the ends of the shaft, levers fulcrumed on the frame, links connecting said cranks with the last mentioned levers, and a cleaning tool frame also slidably mounted on the guide rod and provided with cleaning tools passing through the table, said cleaning tool frame having a sliding connection with the last mentioned levers whereby the turning of the cranks will cause the levers to lift the tool frame and project the cleaning tools in to the bottles.

6. A bottle cleaning machine, comprising a frame, a continuously moving bottle conveyer passing therethrough, a shaft journaled on the frame, a wheel on the shaft having a cam groove and an interrupted annular flange, a lever fulcrumed on the frame and provided with a roller traveling in the cam groove, links suspended from the frame, beams connected with the links and the lever, a guide rod on one of the beams, a table slidably mounted on the guide rod, a bottle clamping frame also slidably mounted on the guide rod, a lever fulcrumed on one of the beams and having connection with the table and the bottle clamping frame and provided with a roller engaging the annular flange, cranks on the ends of the shaft, levers fulcrumed on the frame, a tool frame also slidably mounted on the guide rod provided with cleaning tools passing through the table, said tool frame having a sliding connection with the last mentioned levers, links connected with the cranks, and means for adjustably connecting the links of the last mentioned levers.

7. A bottle washing machine, comprising a frame, a continuously moving bottle conveyer passing through the frame, a reciprocating frame mounted on the frame, means for reciprocating the frame, suitably driven cranks, levers fulcrumed on the frame, a guide rod carried by the reciprocating frame, a tool frame slidably mounted on the guide rod and having a sliding connection with the last mentioned levers, and links connected with the cranks and having adjustable connections with the last mentioned levers, comprising a shaft passing through slots in said levers, a sleeve keyed on said shaft with pinions on its ends, racks on the levers meshing with the pinions, said links being pivotally mounted on the shaft, a clamping nut threaded on the shaft for clamping the parts in their adjustment, and a handle on the shaft by which it may be

- turned for adjusting the shaft by means of the racks and pinions.
8. A bottle washing machine, comprising a frame, a continuously moving bottle conveyer passing therethrough, a reciprocating frame mounted in the frame, means for reciprocating the same, a guide rod carried by the reciprocating frame, a gear casing slidably mounted on the guide rod, means for lifting the gear casing, spindles carried by the gear casing, bottle clamping brushes on the ends of the spindles adapted to enter the bottles of the conveyer when the gear casing is lifted, pinions on the lower ends of the spindles, intermeshing gears within the gear casing meshing with the pinions, and means for driving the intermeshing gears for turning the spindles.
9. A bottle washing machine, comprising a frame, a continuously moving bottle conveyer passing therethrough, a reciprocating frame mounted in the frame, means for reciprocating the same, a guide rod carried by the reciprocating frame, a gear casing slidably mounted on the guide rod, means for lifting the gear casing, tubular spindles carried by the gear casing, bottle cleaning brushes on the ends of the spindles adapted to enter the bottles of the conveyer when the gear casing is lifted, pinions on the lower ends of the spindles, intermeshing gears within the gear casing meshing with the pinions, means for driving the intermeshing gears for turning the spindles, step bearings in the gear casing for the lower ends of the spindles, water passage ways in the gear casing, tubular plugs fitting within the water passage ways and entering the lower ends of the spindles, packing glands in the lower ends of the spindles around the tubular plugs, flexible water pipes connected with the water passage ways, valves therefor, and cams in the path of the valves for operating the same during the movements of the gear casing.
10. A bottle washing machine, comprising a frame, a continuously moving bottle conveyer passing therethrough, a reciprocating frame mounted in the frame, means for reciprocating the same, a guide rod and a slotted guide frame carried by the reciprocating frame, a gear casing slidably mounted on the guide rod, means for lifting the gear casing, tubular spindles carried by the gear casing, bottle cleaning brushes on the ends of the spindles adapted to enter the bottles of the conveyer when the gear casing is lifted, pinions on the lower ends of the spindles, intermeshing gears within the gear casing and meshing with the pinions, a beveled gear on one of the intermeshing gears, a shaft journaled in the gear casing, a beveled gear thereon meshing with the other beveled gear, a sprocket wheel on the shaft, a guide roller surrounding the shaft and a guide roller mounted on the gear casing, said guide rollers bearing within the slotted guide frame, and a driving chain mounted on the frame in engagement with the sprocket wheel for driving the spindles during the movement of the gear casing.
11. A bottle washing machine, comprising a frame, a continuously moving bottle conveyer passing therethrough, a reciprocating frame mounted in the frame, means for reciprocating the same, a guide rod carried by the reciprocating frame, a gear casing slidably mounted on the guide rod, means for lifting the gear casing, tubular spindles carried by the gear casing, bottle cleaning brushes on the ends of the spindles adapted to enter the bottles of the conveyer when the gear casing is lifted, pinions on the lower ends of the spindles, intermeshing gears within the gear casing meshing with the pinions, means for driving the intermeshing gears for turning the spindles, step bearings in the gear casing for the lower ends of the spindles, water passage ways in the gear casing, tubular plugs fitting within the water passage ways and entering the lower ends of the spindles, packing glands in the lower ends of the spindles around the tubular plugs, flexible water pipes connected with the water passage ways, valves therefor, and cams in the path of the valves for operating the same during the movements of the gear casing.
12. A bottle washing machine, comprising a frame, a continuously moving bottle conveyer passing through the frame, a reciprocating table adapted to alternately move with and counter to the conveyer, a bottle clamping frame reciprocating with the table, means for moving the table and the bottle clamping frame toward the bottles to clamp the bottles between them, and a rotary brush carried by the bottle clamping frame for cleaning the bottoms of the bottles.
13. A bottle washing machine, comprising a frame, a continuously moving bottle conveyer passing through the frame at an incline and having openings to receive bottles, a shaft journaled in the frame, means on the shaft for driving the bottle conveyer, a trip lug carried by the shaft, a spring retracted trip rod in the path of the trip lug to be engaged thereby, a lever mounted on the frame and connected with the trip rod, a shutter carried by the lever, a series of inclined rolls adapted to support bottles between them, said bottles being prevented from sliding off of the rolls by the said shutter, worm wheels on the rolls, a shaft journaled on the frame, spiral wheels on the shaft meshing with the spiral wheels on the rolls, means for driving said shaft, rotary brushes mounted in the frame above the rolls, sprocket wheels thereon, sprocket wheels on the rolls, chains connecting the sprocket wheels of the rotary brushes and the sprocket wheels of the rolls, and an inclined guide in line with the rolls to receive the bottles therefrom when the shutter is withdrawn and to guide them into the openings of the conveyer.

14. A bottle washing machine, comprising a frame, a continuously moving bottle conveyer passing through the frame, automatic means for cleaning the bottles during their passage through the machine, a drive shaft journaled on the frame for operating the cleaning means, a clutch for interrupting the driving connection of the driving shaft, a bracket on the frame, a tubular shaft journaled therein, sprocket wheels on the shaft over which the bottle conveyer passes, a rod passing through the tubular shaft, levers on the rod, a stop rod connecting the levers and standing in the path of the bottles to be engaged thereby for swinging the levers, a connecting rod connected with one of the levers, and a bell crank on the frame connected with the connecting rod and with the clutch, whereby the clutch is disconnected when the bottles engage the stop rod.
15. A bottle washing machine, comprising a continuously moving bottle conveyer, a reciprocating table beneath the conveyer alternately moving with and counter to the bottle conveyer, a bottle clamping frame above the conveyer reciprocating with the table, a continuously operated bottle washing means carried by the table, a stationary driv-

ing means operating the bottle washing means, and means for moving the bottle clamping frame and the table toward each other to clamp the bottles between them when the table is moved with the bottle conveyer.

16. A bottle washing machine, comprising a continuously moving bottle conveyer, a reciprocating table beneath the conveyer alternately moving with and counter to the bottle conveyer, rotary brushes carried by the table, continuously operating stationary driving means for the rotary brushes, a bottle clamping frame carried by the reciprocating table above the conveyer, bottle seats on the bottle clamping frame, means for moving the table and the bottle clamping frame toward each other to clamp the bottles of the conveyer between them while the table moves with the conveyer, and means for projecting the brushes through the table into the bottles.

In testimony whereof, I affix my signature, in presence of two witnesses.

DANIEL SCHMID.
